UNITED STATES PATENT OFFICE.

THOMAS OSCAR IVERSON, OF ROCHESTER, MINNESOTA.

FASTENER FOR WINDOW SCREENS OR STORM WINDOWS.

Application filed April 9, 1924. Serial No. 705,277.

To all whom it may concern:

Be it known that I, THOMAS O. IVERSON, a citizen of the United States, and resident of Rochester, in the county of Olmsted and 5 State of Minnesota, have invented certain new and useful Improvements in Fasteners for Window Screens or Storm Windows, of which the following is a specification.

My invention relates to devices for securing 10 a window screen or storm window in place in a window frame, and it consists in the combinations, constructions and arrangements herein described and claimed.

An object of the invention is to provide 15 a fastener, tightener and locker of simple construction which affords facilities for holding a window screen or a storm window securely against the outer vertical guide strip of a window frame of ordinary construction so that the window screen or storm 20 window will not rattle and the passage of dust, cold air or the like between the frame of the window screen or storm window and the window frame is obviated.

25 A further object of the invention is to provide a device of the character described which affords facilities for holding a window screen or a storm window in place in a window frame releasably.

30 A still further object of the invention is to provide a device of the character described which embodies cooperative elements whereby a window screen or storm window of a given width may be held releasably in 35 place in any one of a plurality of window frames which may vary slightly in width.

Other objects and advantages will be apparent from the following description, considered in conjunction with the accompanying 40 drawings, in which—

Figure 1 is a fragmentary perspective view showing a device embodying the invention in position to secure a window screen in place in a window frame,

45 Figure 2 is a section through the structure exhibited in Figure 1, the view being taken substantially along the line 2—2 of Figure 1,

50 Figure 3 is a perspective group view showing the elements of the device separated from one another.

In Figure 1, I show a fragmentary lower corner portion of a window frame 1 of ordinary construction. The window frame 55 1 is provided with the usual outer vertical guiding and retaining strips, such as that

indicated at 2, which serve to retain the upper sash of the window against displacement outwardly from the frame. The sash or frame of a window screen or storm window is ordinarily placed within the window frame from the outer side thereof until the side members of the window screen or storm window abut the outer vertical guide strips 2. Ordinarily, the sash or frame of the window screen or storm window is secured by nails or like fastening devices to the window frame in the position just mentioned, which may cause marring of the window frame when the window screen or storm window is removed and which causes expenditure of considerable time and labor each time a window screen or storm window is to be placed in position in the window frame or removed therefrom.

My invention embodies means whereby the frame of a window screen or storm window may be releasably held in a desirable position in the window frame and therefore instantly removed from or replaced in the window frame without the use of any tools and without the exercise of any unusual skill.

In Figures 1 and 2, the numeral 3 designates the frame of a window screen. Obviously, the frame 3 may be the frame of a storm window.

The device comprises a substantially wedge-shaped or tapering fastening, tightening and locking key 4 and two guiding and retaining brackets 5 and 6 respectively, the guiding and retaining bracket 5 being adapted to be secured to the vertical strip 2 of the window frame, the bracket 6 being adapted to be secured to the adjacent side members of the frame 3 and the brackets 5 and 6 having portions adapted to cooperate with each other and to engage with the fastening, tightening and locking key 4, whereby the frame 3 will be secured to the window frame 1 and held tightly against the vertical strips 2. The bracket 5 is formed of a light gauge metal member which is substantially U-shaped in cross sectional contour and includes a flange 7 provided adjacent to the ends of the bracket 5 with openings 8 for receiving screws 9 or like fastening devices for attaching the bracket 5 to the strip 2 or like support. The flange 7 is cut away intermediate its ends and between the openings 8, as at 10, for a purpose to be presently described. The

second flange of the bracket 5 is also cut away intermediate its ends as indicated at 11, the cut away portion thereof extending into the web of the bracket, leaving only end 5 portions 12 and 13 respectively of the second flange, whereby the end portions of the bracket have the form of spaced apart aligned hooks.

The bracket 6 comprises a flat arm 14 10 adapted to rest flatwise against the inner face of a side member of the frame 3 and to be secured to the latter by a bolt 15 which extends through an opening in the side member 15 of the frame 3 and through an elongated opening or slot 16 in the arm 14 and a nut 17 which is screwed on the shank of the bolt against the arm 14. The bracket 6 also includes an arm 18 which extends substantially at right angles to the arm 14 and is 20 bent laterally outward and thence rearwardly adjacent to its outer end to provide a hook portion 19.

From the foregoing description of the various parts of the device, the operation thereof 25 may be readily understood. The bracket 6 is secured by the bolt 15 and the nut 17 against the inner face of a side member of the frame 3 so that the arm 18 will abut the inner wall of the cut away portion 11 when the frame 3 is disposed in the window frame 1 with said one side member of the frame 3 adjacent the stop strip 2. With this arrangement, the bill of the hook portion 19 will be received in the cut away portion 10 30 of the bracket 5 and the hook portion 19 will be disposed between the hook portions at the ends of the brackets 5. Since the hook portion 19 is bent reversely to the ends of the hook portions at the ends of the bracket 40 5, the hook portion 19 and the hook portions at 12 and 13 will cooperate to provide a guideway in which the tapering or wedge-shaped fastening, tightening and locking key may be inserted to lock the bracket member 6 to the bracket member 5 and thus hold the frame 3 against displacement from the window frame 1. The tapering locking key 4 is provided at its wider end with a laterally turned portion 20 which is adapted to 50 serve as a handle and may be conveniently grasped when it is desired to manipulate the locking key. It will be manifest that the engagement of the tapering locking key 4 with the bracket 5 and with the hook portion 55 19 of the bracket 6 will tend to cam these opposed members apart so that one side member of the frame 3 will be held tightly against the strip 2 and rattling of the frame 3 in the window frame 1 is prevented. As 60 illustrated in Figure 3, the bolt 15 may have flattened sides as indicated at 21 and thus be adapted to engage with the side walls of the elongated opening 16 to prevent turning of the bolt 15 about its longitudinal axis independently of the bracket 6. A washer 22 is

in place on the shank of the bolt 15 between the head 23 of the latter and the outer face of said one side member of the frame 3. The head 23 of the bolt 15 is provided with a slot 24 adapted to be engaged by the blade of a screw driver or like tool so that the frame 3 may be tightened against the strips 2 from the outer side of the window if required. To tighten the frame 3 against the strips 2 from the outer side of the window, the nut 17 70 is loosened slightly and the bolt 15 is turned slightly through the use of a screw driver, which will cause the bracket 6 to swing upward and will thus effect tightening of the frame 3 against the strips 2. The bolt 15 75 thus may be termed an auxiliary tightener. In adjusting the device, the nut 17 is loosened, the bracket 6 is moved transversely of the direction of length of the bolt 15 to adjust the bracket 6 in respect to the bracket 5, the wedge shaped key is placed in position and the nut 17 is tightened until the frame 3 is secured firmly against the strips 2. The provision of the elongated opening 16 also permits movement of the bracket 6 transversely to the direction of length of the bolt 15 to an extent sufficient to adapt a frame 3 which carries the bracket 6 to be secured in place within any one of a plurality of window frames 1 which may vary slightly in width and each be provided with a bracket 5 for cooperating with the bracket 6.

It will be obvious that two or more sets of the brackets 5 and 6 may be employed to 100 secure the frame 3 in place within the window frame 1, the respective sets of brackets 5 and 6 being disposed at opposite sides of the window frame.

Obviously, my invention is susceptible of embodiment in forms other than that illustrated in the accompanying drawing and I therefore consider as my own all modifications and adaptations of the form of the device herein described which fairly fall within the scope of the appended claims.

I claim:—

1. A fastener for securing a window screen or storm window to a window frame comprising a bracket attachable to an outer vertical guide strip of the window frame, said bracket comprising a pair of spaced apart hook portions having the web portions thereof proximate to the adjacent face of a side member of the frame for said window screen or storm window, a second bracket attachable to said side member of the frame of the window screen or storm window and having a hook portion bent reversely to the hook portion of said first named bracket and disposed between said first named hook portions, and a tapering locking key insertable between the first named hook portions and the hook portion of the second named bracket.

2. A fastener for securing a window

screen or storm window to a window frame comprising a bracket attachable to an outer vertical guide strip of the window frame, said bracket comprising a pair of spaced 5 apart hook portions having the web portions thereof proximate to the adjacent face of a side member of the frame for said window screen or storm window, a second bracket having an attaching portion adapted 10 to rest flatwise against said side member of the frame of the window screen or storm window and having an elongated opening therein, a bolt insertable through said elongated opening and through an opening in 15 the side member of the frame of the window screen or storm window, and a nut adapted to be screwed on the shank of said bolt against said attaching portion of the second named bracket, said second named 20 bracket including a hook bent reversely to said first named hook portions, and a tapering locking key adapted to be inserted between said first named hook portions and the second named hook portion.

25 3. A fastener for securing a window screen or storm window to a window frame

comprising a bracket attachable to an outer vertical guide strip of the window frame, said bracket comprising a pair of spaced 30 apart hook portions having the web portions thereof proximate to the adjacent face of a side member of the frame for said window screen or storm window, a second bracket having an attaching portion adapted 35 to rest flatwise against said side member of the frame of the window screen or storm window and having an elongated opening therein, a bolt insertable through said elongated opening and through an opening in 40 the side member of the frame of the window screen or storm window, and a nut adapted to be screwed on the shank of said bolt against said attaching portion of the second named bracket, said second named bracket including a hook bent reversely to said first 45 named hook portions, a tapering locking key adapted to be inserted between said first named hook portions and the second named hook portion, said bolt being flattened longitudinally to engage with the side walls of the elongated opening.

THOMAS OSCAR IVERSON.
